UNITED STATES PATENT OFFICE.

ALEXANDER P. MORROW, OF ELMIRA, NEW YORK.

DRILL-CHUCK.

No. 893,348.

Specification of Letters Patent.

Patented July 14, 1908.

Application filed October 24, 1907. Serial No. 399,052.

To all whom it may concern:

Be it known that I, ALEXANDER P. MORROW, a citizen of the United States, residing at Elmira, in the county of Chemung and State of New York, have invented certain new and useful Improvements in Drill-Chucks; and I do hereby declare the following to be a full, clear, and exact description of the invention, such as will enable others skilled in the art to which it appertains to make and use the same.

This invention relates to chucks, and more particularly to that class of devices in which a tubular shell or case is employed having a revoluble head therein engaging gripping jaws which are slidably mounted upon or within the case and adapted to be advanced by the rotation of the head so as to grip an article and to release their grip and recede into the case when the direction of rotation of the head is reversed.

The objects of the invention are to produce an efficient, durable and inexpensive chuck of the character referred to consisting of few parts which may be easily assembled or taken apart, and to provide an anti-friction bearing external to the head adapted to sustain end-thrust and hold the head and case together, and further, to dispense with the usual screw-threaded connection between the revoluble head and case or shell and thus avoid the trouble and inconvenience resulting from injury to the threads upon the head, which frequently occurs when the head is made to project beyond the case in unscrewing the same sufficiently to advance or retract the gripping jaws.

The invention will first be hereinafter particularly described, with reference to the accompanying drawings, which are to be taken as a part of this specification, and then pointed out in the claims at the end of the description.

In said drawings, Figure 1 represents a perspective view with parts broken away of a clutch embodying my invention; Fig. 2 is a longitudinal sectional elevation of the same; Fig. 3 is a collective view in side elevation, partly in section, of the several un-assembled parts of a clutch embodying my invention, and Fig. 4 is a transverse section, taken on the line 4--4 of Fig. 2, looking in the direction of the arrow.

Referring to the drawings, in which corresponding parts are denoted by similar

letters in different views, the letter A may denote a tubular body or case having a frusto-conical section a, which is slotted lengthwise to provide suitable guides for a series of jaws B, which are slidably fitted in said slots. Within the case is fitted a revoluble head C, having a section C' screwed into its inner end, so that when rotated, (the inner section C' being stationary,) the screw-threaded connection will cause the inner section to either advance or recede into the main body C of the head, according to the direction of rotation, thereby advancing or retracting the jaws with which said section C' is connected.

The periphery of the head C is smooth, or without screw-threads, and adapted to fit a correspondingly smooth bore of the tubular body or easing, and these two parts are connected together in such manner as to permit free rotation one upon or within the other, while preventing endwise movement or separation thereof, by means of an anti-friction bearing which, in the form shown, consists of a series of balls E running in an annular groove e in the periphery of the head and a corresponding groove e' on the inner side of the tubular body or case, the latter groove being formed partly in the main portion or body of the case and partly in a detachable section or nut A', which may be screwed into an interiorly threaded recessed end of the case, as shown in Fig. 2 of the drawings. As will be seen, the section C' of the head is formed or provided with, preferably, dovetail grooves or recesses c, adapted to receive correspondingly shaped tenons b, on the sliding jaws B, which latter are fitted in the slots of the frusto-conical portion of the case and are provided with marginal ribs b', engaging recesses a' which extend along the margins of said slots, so that the jaws are supported by said marginal ribs within the slots, and are confined therein against radial movement by means of a sleeve D, having a frusto-conical portion d, which overlies the frusto-conical portion of the case; said sleeve being screwed upon the case, as shown, or otherwise secured thereto. Rotation of the case independently of the section C' of the head is prevented, while longitudinal movement of the latter is permitted, for the purpose of advancing or withdrawing the gripping jaws, by the described connection between said parts. For greater strength

and security against independent rotation of the reciprocating section C' of the head, external lugs or projections c' may be formed on its periphery directly in the rear of the dovetail slots therein, so as to engage the longitudinal slots in the frusto-conical section of the case. Said lugs may also serve as an abutment or stop to limit the rearward movement of the section C' within the head.

Exterior milled surfaces of the case and sleeve may be provided, as shown, to afford a firmer hold upon said parts when it is desired to unscrew them, or for the purpose of 15 rotating the case upon the center-piece or head, or vice versa, when it is desired to advance or retract the jaws. The center-piece or head is recessed as usual to receive a tool or shank F, by which rotary movement may 20 be imparted to the head while the tubular case is held stationary.

In operation, rotation of the head in one direction will gradually advance the gripping jaws, causing them to move without rotating 25 along the inclined surface of the frusto-conical portion of the case, as indicated in Fig. 2, until they firmly grip the shank of a tool or other article, and by a reverse movement of the head the jaws will be retracted or caused 30 to recede into the frusto-conical portion of the case in the usual manner, but by reason of the anti-friction bearing, which takes the end-thrust and permits free and easy rotation, the desired results are accomplished 35 without the exertion and wear and tear incident to using chucks of a similar character as heretofore constructed, and there are no screw-threads on the head to be exposed outside of the casing, with consequent liability 40 to injury, while the threaded connection between the telescopic sections of the head is

protected by being inclosed within the case, all of which contribute to the general efficiency and durability of the device.

It will be understood, of course, that various changes might be made in the details and arrangement of parts without departing from the spirit and scope of my invention, and hence I do not desire to be restricted to the specific construction and arrangement 45 shown and described.

Having thus described my invention what I claim as new and desire to secure by Letters Patent of the United States is:

1. In a chuck, a revoluble case and jaws 55 adapted to be operated thereby, in combination with a head within the case having a smooth cylindrical exterior, there being an annular race-way between the case and head, and anti-friction devices in said race-way serving the double purpose of a bearing 60 and a key to prevent end movement.

2. In a chuck, a revoluble case having a conical section with slots extending longitudinally thereof and jaws slidably engaged 65 with said slots, in combination with an internally threaded head having an externally threaded section screwed therein, said section being connected with said jaws so that they are moved longitudinally and radially 70 by rotation of the case or head, and projections on said threaded section engaging the slots in the case for co-operative action in preventing independent rotation and to limit rearward movement of said threaded 75 section.

In testimony whereof I affix my signature in presence of two witnesses.

ALEXANDER P. MORROW.
